United States Patent Office

Des. 228,399
Patented Sept. 18, 1973

228,399

THREE WHEEL JUVENILE VEHICLE

David K. Camfield, Olney, Ill., assignor to
AMF Incorporated

Filed Mar. 6, 1972, Ser. No. 232,350

Term of patent 14 years

Int. Cl. D21—01

U.S. Cl. D34—15 AL

FIG. 1

FIG. 5

FIG. 4

FIG. 1 is a front perspective view of a three wheel juvenile vehicle showing my new design;

FIG. 2 is a top plan view thereof;

FIG. 3 is a side elevational view thereof, the opposite side being a mirror image thereof;

FIG. 4 is a front elevational view thereof;

FIG. 5 is a rear elevational view thereof.

I claim:

The ornamental design for a three wheel juvenile vehicle, substantially as shown.
